VARIABLE OUTPUT WELDING
TRANSFORMER

Edward A. Hobart, Troy, Ohio, assignor to The
Hobart Brothers Company, Troy, Ohio, a cor-
poration of Ohio

Application October 22, 1947, Serial No. 781,341

8 Claims. (Cl. 171—119)

1

This invention relates to transformers of the type commonly employed in conjunction with welding and is concerned primarily with such a transformer having a variable output.

At the present time it is a common and well accepted practice in the field of arc welding to employ a transformer for the alternating current which may be adjusted to vary the amperage output. Thus, the transformer may be adjusted to accommodate the particular requirements of any specified job.

With the now known variable output transformers one of the coils which may be either the primary or secondary is anchored in a fixed position whereby it is rendered stationary. The other 15 of the coils is then mounted so that it is movable with respect to the fixed coil. The amperage of the current which is delivered by the transformer depends directly on the relative position of the primary and secondary coils. Thus, by adjusting this relative position the amperage is varied as occasion demands.

With the above noted conditions in mind the present invention has in view, as its foremost objective, the provision of a variable output transformer of the type indicated in which both the coils are movably mounted. In carrying out this idea the coils are vertically arranged and mounted on a screw stem having oppositely threaded sections. One of the coils is supported from one of the threaded sections and the other coil from the other threaded section. This arrangement presents certain definite advantages.

Due to the vertical disposition of the coils any relative movement therebetween is accompanied by the movement of one coil against the force of gravity, while the movement of the other coil is aided by gravity action. By mounting the coils in the manner above specified the two movements are compensatory and all adjustments are made with minimum ease and require a uniformity of exertion. Thus, we do not have the condition which previously existed wherein one coil could be easily lowered with very little effort but which was raised only with a much greater exertion. With the arrangement of this invention the same effort is required to move the coils together as it is to separate them.

By mounting both of the coils on the oppositely threaded stem the time required for making any particular adjustment is greatly reduced. It is to be remembered that there is a definite limit as to the pitch of the screw threads which may be employed. If this pitch is too great, one of the coils could slide down the screw threads under

2

the influence of gravity action. Hence, the pitch of the threads must be held within a certain limit. For any given pitch one turn of the screw stem will move the coils together at twice the rate which would obtain were only one of the coils movably mounted on the stem.

With the variable output transformers heretofore employed great difficulty has been experienced in eliminating or holding to a desirable minimum the "hum" or noise which attends the magnetic vibration. This is largely due to the fact that when a movable core type of transformer is employed any metal part through which the magnetic flux passes is subject to vibration and becomes noisy unless the fits are highly accurate.

If the core is fixed and one coil is stationary, the latter is securely affixed to the magnetic core. The screw which operates the movable coil of necessity has to be supported at the two ends by bearings and these bearings are subject to the same vibration and noise that attend the movable core.

Another highly important object of the present invention is the reduction or substantial elimination of this magnetic vibration. This is achieved by the above outlined arrangement by which both of the cores are movably mounted on the screw stem having oppositely threaded sections. With this arrangement none of the vibration is transmitted to the bearings as it occurs only between the two supports suspended from the screw and these supports substantially counterbalance each other. Due to the fact that a small pitch may be employed there are many threads which are effectively engaged by each nut that supports the coils. These threads substantially eliminate any vibration between the coil supporting nut and the stem.

Various other and more detailed objects and advantages of the invention such as arise in connection with carrying out the above noted ideas in a practical embodiment will in part become apparent and in part be hereinafter stated as the description of the invention proceeds.

The invention, therefore, comprises a variable output transformer designed primarily for welding purposes and which is characterized by movably mounting both the primary and secondary coils on oppositely threaded sections of a screw stem. This stem may be rotated to adjust the relative position of the coils and thereby vary the amperage output of the transformer.

For a full and more complete understanding of the invention, reference may be had to the follow-

ing description and accompanying drawings wherein:

Figure 1 is a perspective view of a welding transformer designed in accordance with the precepts of this invention;

Figure 2 is a horizontal section through the transformer being taken about on the plane represented by the line 2-2 of Figure 3;

Figure 3 is a vertical section taken on an enlarged scale;

Figure 4 is another vertical section taken normal to the showing of Figure 3;

Figure 5 is an enlarged detailed view mostly in elevation but partially in section bringing out the mounting at the lower end of the screw stem; and

Fig. 6 is a detailed view of the core frames per se.

Referring now to the drawings wherein like reference characters denote corresponding parts and first more particularly to Figures 3 and 4, the welding transformer of this invention is shown as comprising a base 10 from which depend feet 11 which are adapted to rest on any desirable supporting surface. A casing is identified in its entirety by the reference character C. This casing comprises a lower base section 12 of cylindrical formation and which includes a bottom 13 formed with an opening that receives the base 10. Upstanding from the base section 12 is a main intermediate body section 14 which may be anchored to the base section 12 in any preferred manner such as by the rivets shown at 15.

The intermediate body section 14 is formed with a rear opening 16 which normally is closed by a door 17. The latter may be opened to provide access to the interior of the casing from the rear. Substantially diametrically opposite to the rear opening 16 the body section 14 is formed with a front opening 18 that is normally closed by a front door 19. By opening the door 19 access to the interior of the casing from the front may be had through the opening 18.

Immediately above the main intermediate body section 14 the casing C includes a ventilating section 20. The cap for the casing C is designated 21 and is shown as having a skirt 22 that overlaps the ventilating section 20 to which it is joined. The cap 21 is formed with a window opening at 23 that is normally covered by a transparent pane 24. The cap 21 includes a top wall 25 formed with a central opening 26 that is closed by a handwheel 27 that carries an operating member in the form of a knob 28.

Upstanding from the base 10 are two frame end pieces 29 and 30 between which extend intermediate side braces 31 and 32. Extending between the end pieces 29 and 30 at a distance slightly spaced from the upper ends thereof is a shroud 33 that takes the form of a plate which is anchored to the end pieces by angle bars 34. This plate 33 is formed with a circular opening 35 (see Figures 2 and 3) which accommodates fan blades 36. The fan blades 36 are mounted on the shaft 37 of a motor 38 that is supported from the cross braces 31 and 32 by the ears 39 which are anchored thereto.

Resting on the top of the end pieces 29 and 30 is a core assembly which is identified in its entirety by the reference character A. This core assembly A comprises two complemental open frames F₁ and F₂. These frames are maintained in assembled relation by a bottom piece 40 of channel construction which is supported by the

end pieces 29 and 30 and anchored thereto by the bolt and nut assembly shown at 41. A top piece 42 which is also of channel construction aids in maintaining the assembled relation of the frames F₁ and F₂.

Between the frames F₁ and F₂ there is defined a central passage or recess 43 for a purpose to be later explained. Inasmuch as the frames F₁ and F₂ are of complemental or duplicate construction, only one of them needs here be described in detail for the purposes of this specification.

Upon referring to Figure 4, it will be noted that each of these core frames comprises a front frame member 44 and a rear frame member 45, the two being of angle bar construction. The top piece which has been identified generally as 42 also comprises a pair of angle bars which are anchored to the frame members 44 and 45 by the bolts shown at 46. The frame members 44 and 45 include upper and lower side portions 47 and 48, respectively, which are off-set with relation to each other and joined by a shoulder 49. Each of the frames F₁ and F₂ includes a centrally disposed core piece 50.

It is notable that the side parts 48 are anchored to the bottom piece which has been identified generally as 40 by bolts shown at 51. This bottom piece 40 actually takes the form of the two angle bars that are clearly brought out in Figure 4 and which are anchored to the end pieces 29 and 30 by the bolts 41. Laminations shown at 9 are clamped between the front and rear angle bars making up the frames F₁ and F₂. It is evident that the frame F₁ provides an upper space 52 and a lower space 53 with the latter larger than the space 52 which increased dimension is provided by the shoulders 49.

One coil of the transformer which, for illustrative purposes, may be taken as the primary coil is shown at 54. This coil is disposed about the central core frame parts 50 and is designed for vertical reciprocation mainly within the spaces 52 although the coil 54 may be moved down into the larger spaces 53. The other coil which, in this instance, will be the secondary is shown at 55 which is also disposed about the central core frame parts 50. The coil 55 is designed for vertical reciprocation in the larger spaces 53 and has a central bore represented by the broken lines of Figures 3 and 4 which is sufficiently large to receive the coil 54. Thus, the coil 54 is adapted to be received either partially or entirely within the coil 55.

A screw stem 56 extends from the handwheel 27 at the top down between the angle bars making up the top piece 42, through the passage or space 43, between the frames F₁ and F₂ into the bottom piece 40 where the lower end is received between the angle bars making up this piece. This screw stem 56 has oppositely threaded screw sections 57 and 58. As shown in Figure 3, the lower end of the screw stem 56 is received in a bearing assembly 59 carried by the bottom piece 40 and its upper end passes through another bearing assembly 60 carried by the top piece 42.

The coil 55 is anchored to a support 61 by the nut and bolt assembly shown at 62. The support 61 has an opening through which the screw stem passes and carries a nut 63 into which is threaded the screw section 58. Thus, the coil section 55 is supported from the screw section 58.

Likewise, the coil 54 is anchored to a support 64 by bolts comparable to the bolts 62 and the support 64 carries a nut 65 that is threaded into

the screw section 57 of the stem 60. Thus, the coil 54 is supported from the screw section 57. The upper end of the screw stem 56 is drivably connected to the handwheel 27 by the connection shown at 66.

Positioned within the cap 21 at a point where it may be viewed through the window opening 23 is a dial face 67 which takes the form of a segment of a cylinder. The dial face 67 is carried by a plate 68 which in turn carries a sheave 69 that is freely journaled about the screw stem 56. A coil spring 70 is disposed about the screw stem 56 and has a tendency to normally urge the dial face 67 in one direction of rotation. A cable 71 is positioned over the sheave 69 and tension on this cable opposes the tendency of the spring 70. Thus, if this tension is sufficiently great, the dial face 67 is rotated in a direction opposite to that caused by the spring 70.

A lever 72 is pivotally mounted as indicated at 73 on the rear frame part 45 of the frame F2 back of the shoulder 49 of this frame. The upper end of the lever 72 carries a hook 74 to which the cable 71 is anchored. A bar 75 is secured to the coil support 64 and carries at its free end a roller 76 that engages the arm 72. The pivot 73 for the lower end of this lever 72 is so positioned that when the coil 54 moves upwardly the roller 76 urges the lever 72 outwardly thereby exerting a tension on the cable 71 and rotating the dial face 67 against the influence of the spring 70. When the coil 54 is lowered the roller 76 is retracted and the spring 70 becomes effective to rotate the dial face 67 in the opposite direction. This mechanism for actuating the dial face is illustrated, described, and claimed in the co-pending application of Edward A. Hobart et al., Serial No. 727,830, filed February 11, 1947, entitled Alternating current vertical welder. Said application issued as Patent #2,457,372 on December 28, 1948.

Opposite to the opening 16 there is a panel 17 which carries a terminal represented at 78. Access to this panel may be had by opening the door 17. Likewise, there is another panel 19 opposite to the opening 18 and this panel carries a terminal shown at 80. These terminals 78 and 80 are used in making the electric connections to the primary and secondary coils 54 and 55.

As is clearly brought out in Figure 4, a pair of condensers may be carried by the base 10 beneath the shroud 33.

Operation

While the operation of the above described mechanism is believed to be obvious, it may be briefly described by noting that when the user of this welding transformer is desirous of adjusting the amperage output he avails of the knob 28 to rotate the handwheel 27. A corresponding rotation is thereby imparted to the screw stem 56 and depending on the direction of rotation the primary coils 54 and 55 are either moved in a direction tending to separate them or towards each other.

As the amperage output depends on the relative position of these coils 54 and 55, any adjustment in this relative position is accompanied by a turning of the dial face 67 whereby the operator may be reading this dial face to ascertain just what current is being delivered by the transformer.

While the preferred specific embodiment of the invention is hereinbefore set forth, it is to be clearly understood that the invention is not to

be limited to the exact construction illustrated and described, because various modifications of these details may be provided in putting the invention into practice within the purview of the appended claims.

What is claimed is:

1. In a welding transformer, a substantially vertical screw stem having oppositely threaded sections, a primary coil supported from one of said threaded sections and having its axis coincident with said stem, and a secondary coil supported from the other of said threaded sections and having its axis coincident with said stem, said coils being independent of one another so far as direct electrical connections are concerned.
2. In a welding transformer, a screw stem having oppositely threaded sections, a primary coil disposed about said screw stem and supported from one of said threaded sections, and a secondary coil also disposed about said screw stem and supported from the other of said threaded sections, one of said coils being larger than the other and having a bore sufficiently great to receive the smaller of said coils.
3. In a welding transformer, a screw stem having oppositely threaded sections, a primary coil disposed about said screw stem and supported from one of said threaded sections, and a secondary coil also disposed about said screw stem and supported from the other of said threaded sections, said secondary coil being larger than said primary coil and having a bore sufficiently large to receive said primary coil.
4. In a welding transformer, a screw stem having oppositely threaded sections, a primary coil disposed about said screw stem and supported from one of said threaded sections, a secondary coil also disposed about said screw stem and supported from the other of said threaded sections, and a hand-wheel carried by said screw stem and operable to rotate said screw stem.
5. In a welding transformer, a screw stem having oppositely threaded sections, a pair of core frames arranged on opposite sides of said screw stem, each of said core frames defining upper and lower spaces, one larger than the other, a primary coil disposed in one pair of corresponding of said spaces and about said screw stem, means for supporting said primary coil from one of said threaded sections, a secondary coil in the other pair of said spaces, means for supporting said secondary coil from the other of said threaded sections, and means slidably guiding said coils on said core frames and preventing rotation of said coils whereby rotation of said screw stem will move said coils relatively.
6. In a welding transformer, a casing, a screw stem mounted in said casing and having oppositely threaded sections, a pair of core frames arranged on opposite sides of said screw stem so as to define a passage enclosing said screw stem and rigidly connected together, each of said core frames defining an upper reduced space and a lower enlarged space, a primary coil positioned in the upper spaces of said core frames about said screw stem, means for supporting said primary coil from one of said threaded sections, a secondary coil positioned in the larger spaces of said core frame about said screw stem, means for supporting said secondary coil from the other of said threaded sections, and means slidably guiding said coils on said core frames and preventing rotation of said coils whereby rotation of said screw stem will move said coils relatively.

smaller of said coils may be telescoped to any desired degree with the larger of said coils, and means extending along said passage and connected with said supporting means operable for moving said coils in respectively opposite directions for varying the coupling therebetween, said means also being operable for rigidly retaining said coils in any of their positions of adjustment relative to each other.

EDWARD A. HOBART.

7. In a welding transformer, a screw stem having oppositely threaded sections, a pair of core frames on opposite sides of said screw stem defining a passage enclosing said screw stem and having walls parallel with the axis of said screw stem, means rigidly connecting said frames together and journalling said screw stem at its opposite ends, a nut screwed onto each threaded section of said stem, a coil support carried by each nut and in sliding engagement with the walls of said passage, a primary coil anchored to one of said supports, and a secondary coil anchored to the other of said supports, whereby rotation of said screw stem will move said coils relatively, and said coils being adapted for telescoping together.

8. In a welding transformer, a primary coil, a secondary coil, said coils being adapted for telescoping, a pair of independent magnetic core frames extending through and around said coils, said frames being spaced apart and rigidly connected together at their ends, whereby they define a passage having parallel walls, supporting means connected with said coils and engaging said walls for slidably guiding said coils in relatively rectilinear reciprocation whereby the
